UNITED STATES PATENT OFFICE.

WILEY ROSE, OF EDDYVILLE, ILLINOIS.

QUILT-HOLDING ATTACHMENT FOR SEWING-MACHINES.

SPECIFICATION forming part of Letters Patent No. 391,081, dated October 16, 1888.

Application filed January 12, 1888. Serial No. 260,550. (No model.)

To all whom it may concern:

Be it known that I, WILEY ROSE, a citizen of the United States, residing at Eddyville, in the county of Pope and State of Illinois, have 5 invented a new and useful Quilt-Holding Attachment for Sewing-Machines, of which the following is a specification.

My invention relates to improvements in quilt - holding attachments for sewing - machines; and it consists in certain novel features, hereinafter described and claimed.

In the drawings, Figure 1 is a plan view of my improved apparatus, showing it applied to a sewing-machine. Fig. 2 is a side view of 15 the same. Fig. 3 is a side view showing the track folded. Fig. 4 is a vertical section on the line xx of Fig. 1. Fig. 5 is a similar view on line yy , Fig. 1. Fig. 6 is a detail view showing the manner of mounting the rollers on 20 the sides of the carriage.

Referring to the drawings by letter, A designates an ordinary sewing-machine having my improved quilting-frame applied thereto. The quilting-frame comprises the track B and 25 the carriage C, traveling thereon. The track consists of the parallel rails D D, which are made in two equal sections, connected at their centers by hinges dd , and the cross-bars E, secured to and between the rails to brace and strengthen 30 the same. The rails are made substantially L-shaped in cross-section, thereby providing the inwardly-projecting shoulders or flanges d' , on which the rollers of the carriage run. The cross-bars at the ends of the track are 35 provided with sockets e , adapted to receive the upper end of a removable prop or support, F. These props or supports are of different lengths, so that when the device is in use the track will be inclined from the operator, as 40 shown in Fig. 2, in order that the carriage may roll from the sewing-machine by reason of its own gravity.

The sewing-machine is tilted to correspond with the inclination of the track by means of 45 the removable blocks G, placed under its front legs, as shown in Fig. 2.

The track is secured upon the sewing-machine table by means of the hooks H, having threaded shanks I, inserted upward through 50 the rails past the sides of the table. Securing-nuts h are mounted on these threaded shanks and are turned down against the upper

side of the rails, thereby causing the claws i to take into the under side of the machine-table, as will be readily understood. The track is 55 thus secured firmly to the machine-table and cannot be accidentally displaced.

The carriage consists, primarily, of the longitudinal side bars, J J, and the transverse end pieces, K K. The side bars, J, have recesses 60 in their sides, in which are secured the plates L, having pintles l projecting laterally from their upper ends, and upon these pintles are mounted the carrying-rollers M, which rest upon the shoulders or flanges of the rails and 65 support the carriage. The end pieces, K, are castings, having their central portions, k , reduced or cut away, as shown, so as to pass readily under the presser-foot of the sewing-machine. These castings are further provided 70 with the integral standards N near their opposite ends, and on their inner sides they are provided with the sockets O. The upper ends of the standards N at the rear end of the carriage are provided with the transverse bearings n , and the upper ends of the standards at the front end of the carriage are provided with the notches or open-ended slots n' . The roller-bars P, on which the quilt is wound, are provided at their ends with journals p , which are 75 engaged in the bearings n and the notches n' , as shown. The roller-bars are first engaged in the bearings n , and the opposite ends are then dropped into engagement with the notches n' , as will be understood. On the rear ends of 80 the roller-bars I provide the ratchet-wheels Q, which are engaged by the gravity-pawl R, pivoted on the standards below the ratchet-wheels, and having their lower ends weighted, as shown, so as to be held positively in engagement with the ratchet-wheels. 85

The sockets O on the end piece at the front end of the carriage are closed on all four sides; but the sockets on the end piece at the rear end of the carriage are open on one side. This construction permits the ready application and removal of the stretching-bars S, which have 95 their front ends inserted in the front sockets, after which they are swung horizontally to cause their rear ends to engage the rear three-sided sockets. The ends of the stretcher-bars are then secured in their respective sockets by the removable pivot-pins T.

In practice the quilt to be finished is mounted

on the roller-bars and allowed to hang from and between the same, as shown. The stretching-bars are then placed in position, as just described, over the depending portion of the quilt, thereby stretching the same smooth and even. The carriage is then placed on the track, (previously applied to the sewing-machine,) the arm of the sewing-machine projecting over the inner roller-bar, so as to bring the needle over the stretched portion of the quilt. The machine is then operated in the usual manner to form the rows of stitching or quilting, and after each row is finished the roller-bars are rotated so as to bring an unstitched portion of the quilt in position to be operated upon by the machine.

It will be observed that my device is very simple in its construction, and consequently is not liable to get out of order, and if any part should be broken it can be replaced at a slight cost. When not in use, it can be put aside in a small space, as the rails are so proportioned that the sections of the track can be folded upon each other without removing the carriage.

Having described my invention, I claim—

1. The combination of the track having rails provided with inwardly-projecting flanges and made in sections having their adjacent ends hinged together, and the carriage provided with rollers resting on the flanges of the track,

whereby one section of the track may be folded over the carriage onto the other section, as set forth.

2. The combination, with the track, of the carriage traveling thereon and composed of side bars, and the end bars having reduced central portions and connecting the side bars, the said end bars having sockets on their inner faces, the standards on the end bars, the removable roller-bars journaled in the standards, and the stretcher-bars removably secured in the sockets on the end bars, as set forth.

3. The combination of the track and the carriage traveling thereon, the said carriage comprising the side bars, the end bars connecting the side bars and provided with sockets on their inner sides and having integral standards on their upper sides, the removable roller-bars journaled in the upper ends of said standards, the stretcher-bars removably secured in the sockets on the end bars, the ratchet-wheels on the roller-bars, and the gravity-pawls pivoted on the sides of the standards and having their upper ends engaging the ratchet-wheels, substantially as specified.

WILEY ROSE.
